STEAM CONTROL SYSTEM FOR LOCOMOTIVE CYLINDERS AND STEAM CHESTS

Charles Stern, Jersey City, N. J.

Application September 20, 1941, Serial No. 411,728

10 Claims. (Cl. 121—137)

This invention relates to steam control system for locomotive cylinders and valve chambers while locomotive is drifting or coasting and at rest.

An object of this invention is to provide an automatic steam control system for a locomotive, of the character described, comprising means for eliminating formation of vacuum in the cylinders, and preventing formation of carbon and assuring positive lubrication with a minimum of steam consumption, means being further provided to protect the locomotive against accumulated pressure in the cylinders or valve chambers while standing in the terminal or roundhouse.

Another object of this invention is to provide in a system of the character described, means for admitting auxiliary steam at a predetermined pressure to the valve chambers and steam cylinders immediately upon shutting off of the main throttle, whereby at no time is steam absent from the valve chambers and cylinders, thus effectively preventing admission of air to the valve chambers and cylinders, flashing of oil, and formation of carbon, the arrangement being such that the auxiliary steam is admitted to the cylinders and cylinder valves automatically and without the attention of the locomotive operator.

Still another object of this invention is to provide in a system of the character described, means to admit steam direct to the admission ports of the cylinders and to the valve chambers regardless of the position of the valve, while drifting, thereby preventing admission of air and gases therein and providing sufficient steam pressure for atomizing the oil and cushioning the pistons in the cylinders, rods, bushings and all reciprocating parts of the steam engine.

Yet another object of this invention is to provide in a system of the character described, a drifting throttle and balancing steam valve which shall be relatively inexpensive to manufacture, positive in operation, and practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawings, in which is shown one of the various possible illustrative embodiments of this invention,

Fig. 1 is a side, elevational view of a locomotive

provided with steam control system for drifting locomotive, embodying the invention;

Fig. 2 is a front, elevational view of the locomotive shown in Fig. 1;

Fig. 3 is an elevational, cross-sectional view through a steam cylinder, drifting throttle and balancing steam valve, embodying the invention;

Fig. 4 is a view similar to Fig. 3, but disclosing the position of the apparatus while the locomotive is drifting;

Fig. 5 is a cross-sectional view taken on line 5—5 of Fig. 4; and

Fig. 6 is an elevational, cross-sectional view of air operated valve for actuating a valve controlling admission of low pressure steam to steam cylinder and steam chest while locomotive is drifting.

Referring now in detail to the drawings, 10 designates a locomotive provided with a steam control system, embodying the invention, for the locomotive cylinders and valve chambers while the locomotive is drifting or standing still. The locomotive 10 is provided with the usual steam cylinders 11 on opposite sides of the locomotive, each provided with a valve chamber 12 in which there reciprocates the usual spool valve 13.

Each valve chamber or steam chest is provided with a steam balancing valve 25 mounted thereon. Each balancing valve 25 comprises a housing 25a having an inner cylindrical surface 26 formed with an inwardly extending shoulder 26a at its upper end and being open at the bottom. At the upper end of the cylindrical surface 26 is a cylindrical surface 26b of reduced diameter co-axial with the surface 26. At the upper end of the surface 26b is a valve seat 26c. Extending upwardly from the valve seat 26c is a tubular portion 27 forming a dome chamber 25b and provided with a screw threaded opening 27a at one side. The upper end of tubular portion 27 is closed by a screw plug 27b. The housing 25a is formed with a pair of diametrically opposed, symmetrical, cored passages 28 communicating at their upper ends with the surface 26b and terminating short of the lower end of the casing 25a. The casing 25a is formed with external openings 28a communicating with the lower ends of said cored passages 28.

The housing 25a as shown in Fig. 5 of the drawings, is formed with a second pair of diametrically opposed, symmetrical cored passages 28c disposed in a plane perpendicular to the plane of the passages 28 and communicating at their upper ends with the surface 26b and at their lower ends with the cylinder 26. Said passages

28c thus connect chamber 25b in the dome with chamber 25c within cylinder 26. The lower end of the housing 25a (chamber 25c) is closed by a member 28d having a cylindrical wall 28e projecting upwardly into chamber 25c and formed with two pairs of diametrically opposed openings 28f. One of said pair of openings is shut by the cylindrical surface 26, and the other pair of openings 28f registers with the lower ends of the cored passages 28c, as shown in Fig. 5 of the drawings.

Thus, member 28d may be attached to the lower end of the casing 25a in any of four angular positions, so that there will always be two openings 28f registering with the passages 28c. Member 29d may be fixed to the casing 25a in any suitable manner. Said member is formed with a central opening 28g receiving a nipple or pipe 28h, the lower end of which is screwed within the top of the valve chamber 12.

Slidably mounted within casing 25a is a plunger or valve 29 having an enlarged face 29a at its lower end, slidably engaging within chamber 25c, whereas, the body of the valve slidably engages the surface 26b. When the plunger 29 is in its up position, as shown in Fig. 3, it is seated on valve 26c to close the passages 28, 28c; and when said valve is in its down position as shown in Fig. 5, the passages 28, 28c are open establishing communication between the dome chamber 25b, the lower chamber 25c and hence pipe 28h through the openings 28a.

Screwed within the openings 28a are pipes 29b which are connected at their lower ends to the admission ports 29c of the steam cylinder 11. When steam is admitted through opening 27a into the top of the valve 25, in the manner hereinafter appearing, steam may pass through the passages 28, 28c when the plunger 29 is in its down position, as shown in Fig. 5, to feed steam, from the dome of the boiler, as will be seen hereinafter, both to the steam chest 12 and to the admission ports of the steam cylinder 11.

Within each valve 25 is a spring 29e interposed between the plunger 29 and the plug 28 to exert downward pressure on said plunger.

Normally when the locomotive is running and the throttle is open, steam from the pipes 50 under main throttle pressure supplies sufficient pressure within the steam chests to raise the valves or plungers 29 against the pressure of the springs 29e to cut off communication between the pipes 29b. It will now be understood that normally when the locomotive is running, there is no by-pass between the admission ports of the cylinders through the pipes 29b, thus preventing waste of steam.

The domes of the valves 25, are interconnected by a pipe 35, the ends of which are received into openings 27. Communicating with said pipe 35 is a pipe 36 leading to the dome of the locomotive and receiving steam therefrom at boiler pressure. Interposed in said pipe 36 is a steam valve 37 adapted to be opened upon moving upwardly, in the manner hereinafter appearing, a valve stem 38 projecting below said valve.

Means is provided for automatically moving the valve stem 38 upwardly to open the steam valve 37 and admit steam at boiler pressure to pipes 36 and 35, when the throttle is shut off, for example, when the locomotive is coasting, or upon the train approaching a station, or whenever the train is brought to a halt. To this end,

there is mounted on the locomotive and below the steam valve 37, an air operated valve 39 comprising a fixed cylindrical housing 39a, closed at the bottom by a plug 39b. Connected to said plug 39b is a pipe 39c adapted to supply air under pressure to the interior of said housing. Said housing 39a has a top wall formed with a central opening 39d.

Slidably mounted within said housing is a member 40 having a reduced portion projecting through opening 39d and normally pressed downwardly by a compression spring 40a interposed between said member and the top wall of the housing 39a. Said member 40 may be hollow and filled with oil, for the purpose of lubrication, the wall of said member being formed with small openings 40b to permit the oil to pass to the inner surface of housing 39a. The upper end of the hollow member 40 may be closed by an adjusting screw 41 adapted to contact the lower end of the valve stem 38.

When there is no air supply through pipe 39c to the housing 39a, member 40 is held down by spring 40a and the steam valve 37 is closed. When air under pressure however is supplied to pipe 39c, in the manner hereinafter explained, member 40 will be moved upwardly against the pressure of spring 40a to lift the stem 38 and open the steam valve 37 to admit steam under boiler pressure to pipe 36, and hence through pipe 35 to the steam control valves 25.

The air pipe 39c leads to a chamber 41 having a bottom wall 41a and a top wall 41b. The bottom wall 41a is formed with a vertical through opening 41c having a valve seat at its upper end. Slidably mounted in said through opening is a valve 41d having a grooved stem within said opening, and a head 41e adapted to be seated on said valve seat.

A compression spring 41f normally holds the valve 41d down in its closed position. Integrally formed with chamber 41 is a second chamber 42 to which is connected a pipe 42a leading to the cab and then to the main air reservoir 42b. There is interposed in said pipe 42a, a valve 42c, located in the cab. The wall between chambers 41 and 42 is provided with an opening 42d, and the bottom wall 41a of the chamber 41 is formed with an opening 42e aligned with said first opening.

Slidably mounted in said openings is a valve 42f having a head at its upper end adapted to close the opening 42d. A coil compression spring 42g normally retains the valve 42f in closed position. When the valve 42f is closed, no air is supplied to the pipe 39c and the stem valve 37 is closed.

Means is provided however for automatically opening the valve 42f and closing valve 41d, upon shutting off the main throttle, whereby to open steam valve 37 and supply steam to the steam balancing valves 25.

To this end, there is supported by a bracket 42h, fixed to the steam chest at the right of the locomotive (looking at Fig. 2), or in any other suitable manner, a steam control valve 43. Said steam control valve 43 comprises a member 44 having a pair of spaced, coaxial, oppositely extending cylindrical portions 45 and 46, the latter being of somewhat greater diameter than the former. The cylindrical portion 46 has a back wall 46a formed with a central opening 46b. The outer end of cylinder 46 is closed by an end wall

47 forming a chamber 48 therewith. Said end wall 47 has an opening 51. Connecting said opening with the main steam pipe 50, is a pipe 49.

The cylindrical wall 48 is formed, meditately the ends thereof, with an opening 46c, connected by a reduced pipe 52 with said pipe 35. Communicating with chamber 48, adjacent the back wall 46a, is a pressure check valve 55 which may be set to open at a predetermined pressure, preferably somewhat above atmospheric pressure, for the purpose hereinafter appearing.

The member 44 is formed with a chamber 58 surrounding the cylindrical member 45 and closed by an end wall 59. Interconnecting the cylindrical wall 45 with the outer wall of the chamber 58, is an exhaust port 60. Said chamber may also be provided with a condensation check or drain valve 61.

Chambers 41, 42 are located between cylinder 46 and chamber 58 and supported on member 43 in any suitable manner.

Slidably mounted on the member 44 for reciprocation, is a member 62, to control valves 41d and 42f, and comprising a piston 65, within the cylindrical member 46, a piston 66, within the cylindrical wall 45, and an axial piston cam 67 interconnecting said pistons. Chamber 58 is interconnected to chamber 48 by pipe 68 closed at one end by spring pressed check valve 69 located on cylinder 46. The piston cam 67 is formed with a pair of spaced, raised cam portions 70 and 71 disposed between the cylinders 45, 46 and adapted to operate air valves 41d, 42f.

Normally, when the locomotive is running and the main throttle is open, steam from main steam pipe 50 passes through pipe 49 to chamber 48, holding control member 62 to the right. In this position, piston 65 closes opening 46c, and piston 66 closes the exhaust port 60. Steam passes through chamber 48, passage 68 and valve 69 (which is unseated), to chamber 58 where steam is trapped. Member 62 will stay to the right because piston 65 is of greater area than piston 66. In this position of said member 62, raised portion 70 of piston cam 67 will lift valve 41d to exhaust any air pressure that may be in pipe 39c, while valve 42f will be held down by spring 42g and air pressure, to close chamber 42 and prevent air from the main reservoir from passing to pipe 39c.

When the main throttle is shut to coast the locomotive or to bring the same gradually to a stop, pressure in main steam pipes 50 and in the steam chests is reduced below the pressure of the steam trapped in chamber 58, causing control member 62 to move to the left, from the position of Fig. 3 to the position of Fig. 4. This operation will lift or open valve 42f and permit valve 41d to drop to closing position. Air from the main reservoir will then pass through pipe 42a, chambers 42 and 41 to pipe 39c, for lifting valve member 40 to open steam valve 37 and admit steam under boiler pressure from the dome of the locomotive to pipes 36 and 35 to the domes of valves 25. Simultaneously, plungers 29 will be lowered by springs 29e, due to reduced pressure in the steam chests, to open communication between pipes 29b; and steam will be supplied directly to the admission ports 29c of the cylinders 12, and also around the plungers through the by-pass passages 28c to the middle of the steam chests regardless of the positions of the spool valves 13.

This operation also seals the back of piston 65

since said piston closes the passage 68. Opening 46b in back wall 46a, is also sealed by collar 70 on piston cam 67. Exhaust port 60 is also opened to exhaust steam from chamber 58. Opening 46c however is uncovered to admit steam from pipe 35 to pipe 52, and to the back of piston 65, to keep the control member 62 to the left. The steam behind piston 65 is maintained at the predetermined pressure of check valve 55.

10 The steam supplied to the steam chests and cylinders prevents vacuum in the cylinders, and formation of carbon and atomizes the oil to assure positive lubrication with a minimum of steam consumption.

15 As the locomotive slows down, pressure builds up in the steam chest slightly, and hence also in main steam pipe 50. Steam passing through pipes 49 hence increase pressure on the left side of pistons 65 sufficiently to overcome the pressure on the opposite side of said pistons, causing the control valve members 62 to move to the right. This operation opens valves 41d and closes valves 42f to exhaust air pressure from pipe 39c and close steam valve 37 to shut off supply of steam from the dome to valves 25.

20 The plungers 29 in valves 25, however, remain in their downmost position since the pressure in the steam chests is not sufficient to raise said plungers against springs 29e. Since the plungers remain down, the steam chests remain in direct communication with the exhaust passages of the locomotive, providing for a release of any accumulated pressure in the steam chests, and protecting the locomotive against movement in case of leaky throttle while standing in the round house or terminal, or in case the steam valve 37 is not completely shut off. Should there be a leak in the main throttle causing pressure to accumulate in the steam chests, steam will pass upwardly through pipe 28h and passages 28c, around plungers 29, and through pipes 29b to the cylinders.

25 The cylinders 11 may be provided with usual relief cylinder cocks 80 connected by pipes 81 to pipe 42a.

30 When the locomotive is standing still for some time, the cab valve 42c is closed and the cylinder cocks 80 are open to exhaust the wet steam from the steam cylinders. Upon starting, the valve 42c is opened to close the cylinder cocks, and this action automatically supplies air to pipe 42a and chamber 42. The main throttle is then opened up to lift the plunger 29 to prevent bypass of steam through pipes 29b, and to shut passage of steam around the plunger. The control system is then in position for automatic operation when the main throttle is next shut off.

35 Usually when a locomotive ties up at a terminal or in a round house, the locomotive operator opens the cylinder cocks. This action shuts off the air supply and prevents possibility of opening of the steam valve 37, and hence prevents admission of steam to the valve chambers and steam cylinders. The operator usually also shuts off the air pump, and this action likewise cuts off the air pressure which is necessary to operate the steam valve 37, thereby giving an additional safety against accidental movement of the locomotive at the terminal or in the round house.

40 When the cylinder cocks 80 are closed by opening of cab valve 42c, air pressure will be supplied to chamber 42 through pipe 42a which leads to the cylinder cocks as well as to said chamber. This action by the locomotive operator supplies

air pressure to the drifting throttle control valve and it is now ready to function when needed. Thus, the operator cannot neglect to supply the necessary air pressure for opening the valve 38 the next time the locomotive coasts since the cylinder cocks 80 must be closed by opening the valve 42c in order to start the locomotive.

When the main throttle valve is opened, steam is admitted through pipe 49 into the cylinder 46 unseating the non-return check valve 69, and supplying steam to the pressure chamber 58. In this position, the plungers 29 in the steam balancing valves 25, are raised by steam pressure from the steam chest overcoming the pressure of springs 29e and preventing by-pass of steam around the steam balancing valves.

The plugs 27b and pipes 49 may be interconnected by pipes 90 connected by pipes 91 to any suitable supply of oil, for the purpose of lubrication.

The cylinder cocks may be operated by steam instead of air.

It will thus be seen that there is provided a device in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accompanying drawings is to be interpreted as illustrative and not in a limiting sense.

Having thus described my invention, I claim as new and desire to secure by Letters Patent:

1. In combination with a steam cylinder and a steam chest for said cylinder, a steam balancing valve comprising a casing, a chamber within said casing, pipes connecting said casing with the admission ports of said cylinder, passages interconnecting said pipes with said chamber, said casing being formed with a second chamber, passages within said casing interconnecting the second chamber with the first chamber, means to connect said second chamber with the steam chest, and a plunger within said casing adapted in one position thereof to close said passages to prevent passage of steam between said pipes and also to prevent passage of steam from said first chamber to said pipes and to said second chamber, and in another position thereof being adapted to open said passages to permit flow of steam from said first chamber to said second chamber and steam chest, and from said first chamber to said pipes.

2. In combination with a steam cylinder and a steam chest for said cylinder, a steam balancing valve comprising a casing, a chamber within said casing, pipes connecting said casing with the admission ports of said cylinder, passages interconnecting said pipes with said chamber, said casing being formed with a second chamber, passages within said casing interconnecting the second chamber with the first chamber, means to connect said second chamber with the steam chest, a plunger within said casing adapted in one position thereof to close said passages to prevent passage of steam between said pipes and also to prevent passage of steam from said first chamber to said pipes and to said second chamber, and in another position thereof being adapted to open said passages to permit flow of steam from said first chamber to said second chamber and steam chest, and from said first chamber to said pipes, means to supply steam to

said first chamber, cylinder cocks on said steam cylinder, means to supply air to operate said cylinder cocks, means to control said air supply, and means controlled by the means to control 5 said air supply, to control said means to supply steam to the first chamber.

3. A steam balancing valve comprising a casing formed with a chamber at the upper end thereof, and an internal cylindrical chamber, a 10 passage connecting said chambers, said casing being formed with a pair of external openings, passages connecting said openings with said first chamber, a plunger within said cylindrical chamber adapted to close said passages in one position thereof, to close communication between said first chamber and said openings and said second chamber, and in another position thereof being adapted to open communication between said first chamber and said openings, and between 15 said first chamber and cylindrical chamber, and spring means to normally maintain said plunger in the second position thereof.

4. A steam balancing valve comprising a casing, having an internal cylindrical chamber open 25 at the bottom, a cylindrical surface of reduced diameter, above said chamber, and co-axial therewith, a valve seat at the upper end of said cylindrical surface of reduced diameter, and a chamber above said valve seat, the wall of said 30 casing being formed with a pair of diametrically opposed, external openings and with passages connecting said openings with said cylindrical surface, and said wall of said casing being further formed with a pair of passages connecting said 35 cylindrical surface with said cylindrical chamber, a plunger within said casing having a flange within said cylindrical chamber, and a body within said cylindrical surface, and a portion adapted to seat on said valve seat, and a member 40 closing the bottom of said cylindrical chamber.

5. A steam balancing valve comprising a casing, having an internal cylindrical chamber open 45 at the bottom, a cylindrical surface of reduced diameter, above said chamber, and co-axial therewith, a valve seat at the upper end of said cylindrical surface of reduced diameter, and a chamber above said valve seat, the wall of said 50 casing being formed with a pair of diametrically opposed, external openings and with passages connecting said openings with said cylindrical surface, and said wall of said casing being further formed with a pair of passages connecting said cylindrical surface with said cylindrical 55 chamber, a plunger within said casing having a flange within said cylindrical chamber, and a body within said cylindrical surface, and a portion adapted to seat on said valve seat, and a member 60 fixed to said casing closing the bottom of said cylindrical chamber, said member having a cylindrical flange projecting up into said cylindrical chamber and formed with openings registering with the passages which connect said cylindrical chamber with said cylindrical surface.

6. A steam balancing valve comprising a casing, having an internal cylindrical chamber open 65 at the bottom, a cylindrical surface of reduced diameter, above said chamber, and co-axial therewith, a valve seat at the upper end of said cylindrical surface of reduced diameter, and a chamber above said valve seat, the wall of said 70 casing being formed with a pair of diametrically opposed, external openings and with passages connecting said openings with said cylindrical surface, and said wall of said casing being fur-

ther formed with a pair of passages connecting said cylindrical surface with said cylindrical chamber, a plunger within said casing having a flange within said cylindrical chamber, and a body within said cylindrical surface, and a portion adapted to seat on said valve seat, a member closing the bottom of said cylindrical chamber, and spring means to press said plunger downwardly in said casing.

7. In combination with a steam cylinder and a steam valve therefor, a steam balancing valve comprising a casing having a wall formed with an internal cylindrical chamber, means to connect said chamber with the steam valve, said casing being furthermore formed with a cylindrical surface of reduced diameter above said cylindrical chamber and with a valve seat at the upper end of said cylindrical surface, and with a dome chamber above said valve seat, the wall of said casing being formed with a pair of diametrically opposed, external openings and with cored passages connecting said openings with said cylindrical surface, the wall of said casing being furthermore formed with a passage connecting said cylindrical surface with said cylindrical chamber, a plunger slidably mounted within said casing having a flange portion within said cylindrical passage, and a body portion adapted to be received within said cylindrical surface, and a portion at its upper end adapted to contact said valve seat, said plunger being adapted to close said passages in the up position thereof and to uncover said passages in the down position thereof, and means to connect said openings with the admission ports of said steam cylinder.

8. In combination with a steam cylinder and a steam valve therefor, a steam balancing valve comprising a casing having a wall formed with an internal cylindrical chamber, means to connect said chamber with the steam valve, said casing being furthermore formed with a cylindrical surface of reduced diameter above said cylindrical chamber and with a valve seat at the upper end of said cylindrical surface, and with a dome chamber above said valve seat, the wall of said casing being formed with a pair of diametrically opposed, external openings and with cored passages connecting said openings with said cylindrical surface, the wall of said casing being furthermore formed with a passage connecting said cylindrical surface with said cylindrical chamber, a plunger slidably mounted within said casing having a flange portion within said cylindrical passage, and a body portion adapted to be received within said cylindrical surface, and a portion at its upper end adapted to contact said valve seat, said plunger being adapted to close said passages in the up position thereof and to uncover said passages in the down position thereof, means to connect said openings with the admission ports of said steam cylinder, and a spring interposed between said plunger and the top of the casing.

9. In combination with a steam cylinder and a steam valve therefor, a steam balancing valve comprising a casing having a wall formed with an internal cylindrical chamber, means to connect said chamber with the steam valve, said casing being furthermore formed with a cylindrical surface of reduced diameter above said cylindrical chamber and with a valve seat at the upper end of said cylindrical surface, and with a dome chamber above said valve seat, the wall of said casing being formed with a pair of diametrically opposed, external openings and with cored passages connecting said openings with said cylindrical surface, the wall of said casing being furthermore formed with a passage connecting said cylindrical surface with said cylindrical chamber, a plunger slidably mounted within said casing having a flange portion within said cylindrical passage, and a body portion adapted to be received within said cylindrical surface, and a portion at its upper end adapted to contact said valve seat, said plunger being adapted to close said passages in the up position thereof and to uncover said passages in the down position thereof, means to connect said openings with the admission ports of said steam cylinder, a spring interposed between said plunger and the top of the casing, and means to supply steam to the dome chamber of said casing.

10. In combination with a steam cylinder and a steam valve therefor, a steam balancing valve comprising a casing having a wall formed with an internal cylindrical chamber, means to connect said chamber with the steam valve, said casing being furthermore formed with a cylindrical surface of reduced diameter above said cylindrical chamber and with a valve seat at the upper end of said cylindrical surface, and with a dome chamber above said valve seat, the wall of said casing being formed with a pair of diametrically opposed, external openings and with cored passages connecting said openings with said cylindrical surface, the wall of said casing being furthermore formed with a passage connecting said cylindrical surface with said cylindrical member, a plunger slidably mounted within said casing having a flange portion within said cylindrical passage, and a body portion adapted to be received within said cylindrical surface, and a portion at its upper end adapted to contact said valve seat, said plunger being adapted to close said passages in the up position thereof and to uncover said passages in the down position thereof, means to connect said openings with the admission ports of said steam cylinder, a spring interposed between said plunger and the top of the casing, means to supply steam to the dome chamber of said casing, cylinder cocks on said steam cylinder, manually controlled means to supply air to said cylinder cocks, and means controlled by said manually controlled means, to control the supply of steam to the dome chamber of said steam balancing valve.

CHARLES STERN.
